MILTON C. J. BILLINGHAM, OF KALAMAZOO, MICHIGAN, ASSIGNOR OF ONE HALF TO
HENRY L. VANDER HORST, OF KALAMAZOO, MICHIGAN.

METHOD OF AND APPARATUS FOR DISINTEGRATING PAPER STOCK.

1,422,251.

Specification of Letters Patent. Patented July 11, 1922.

Application filed July 25, 1918. Serial No. 246,695.

To all whom it may concern:

Be it known that I, MILTON C. J. BILLINGHAM, a citizen of the United States, residing at the city and county of Kalamazoo, State 5 of Michigan, have invented certain new and useful Improvements in Methods of and Apparatus for Disintegrating Paper Stock, of which the following is a specification.

This invention relates to improvements in 10 paper stock treating machines.

My improved stock treating machine is especially designed by me for use in disintegrating old papers for use as paper stock and for use in deinking such stock.

15 The main objects of this invention are:

First, to provide an improved disintegrating or defibreing machine in which the fibres are effectively separated or disintegrated without a grinding or abrading action.

20 Second, to provide an improved stock treating machine in which all of the stock is effectively acted upon.

Third, to provide an improved stock treating machine which is well adapted for disintegrating or defibreing printed papers, also for treatment thereof with deinking solutions.

Further objects, and objects relating to 30 structural details, will definitely appear from the detailed description to follow.

I accomplish the objects of my invention by the devices and means described in the following specification. The invention is clearly defined and pointed out in the 35 claims.

A structure which is a preferred embodiment of my invention is clearly illustrated in the accompanying drawing, forming a part of this specification, in which:

40 Fig. I is a detail side view of my improved stock treating machine.

Fig. II is a vertical section on a line corresponding to line 2—2 of Fig. I, certain parts being shown in full lines for convenience in illustration.

Fig. III is a horizontal section on a line corresponding to line 3—3 of Fig. II.

Fig. IV is a detail horizontal section on a line corresponding to line 4—4 of Fig. II.

50 Fig. V is a detail vertical section corresponding to that of Fig. II, showing a modified embodiment of my invention.

Fig. VI is a detail side elevation of the discharge connections for the embodiment 55 shown in Fig. V.

In the drawing similar reference characters refer to similar parts throughout the several views, and the sectional views are taken looking in the direction of the little arrows at the ends of the section lines. 60

Referring to the drawing: In the embodiment illustrated I provide a tank 1 supported in an upright position on a suitable base 2. In this embodiment the bottom 3 is in the form of an inverted cone terminating in an annular trough 4. A cone 5 projects upwardly from the inner edge of this trough well to the top of the tank. 65

On the top of the tank I mount a chamber 6 having a bottom 7 shaped like an inverted cone with a central discharge opening 8, the tip of the cone 5 being central of this opening and close thereto. On the chamber bottom 7 I arrange blades or plates 9 so as to impart a swirling or rotary motion to the material as it is discharged through the opening 8, the plates being disposed radially and preferably having their ends curved in the same direction as shown in Fig. IV. At the upper end of the cone 80 I provide a plurality of deflector plates 10, the plates being radially disposed relative to the cone, their inner ends in the embodiment shown in Figs. II and III being secured to the cone and their outer ends bolted to 85 the tank. These plates are transversely inclined all in the same direction so as to impart a rotary movement to the material passing downward through the tank. To insure a uniform distribution of the material 90 by the blades they are provided with transverse tapered corrugations 11, that is, the corrugations extend from the front edges of the plates partially across the same. On the rear edges of the plates are curved flanges 95 12 which also aid in giving the desired rotary motion to the material within the tank.

With this arrangement the settling and forming of streams or courses within the tank is prevented, all of the material being kept in circulation. 100

Within the chamber 6 are nozzles 13 disposed oppositely so that the jets or streams indicated at 14 impinge preferably centrally of the chamber. The nozzles are connected 105 by the pipes 15 to the discharges of the rotary pumps 16, the intakes 17 of the pumps being connected to the discharge trough 4 of the tank. Valves 18 control these intakes. 110

In the structure illustrated a motor 19 drives both pumps. A batch of stock is introduced into the tank through the pipe 20 and when fully treated is withdrawn 5 through the pipes 21. With the parts thus arranged the batch of stock is repeatedly circulated through the nozzles and the impinging streams effectively tear up and disintegrate pieces of paper and other stock to 10 be treated without any grinding or abrading action, thus keeping the fibre in good condition. The stock, in passing through the tank is effectively circulated, that is, the forming of streams or courses is prevented 15 so that all of the stock is uniformly treated.

My improved machine is especially well adapted for the treating of stock with de-inking solutions as the stock is not only uniformly treated but is at the same time effectively disintegrated. 20

In the modification shown in Figs. V and VI the conical bottom 22 of the tank extends to a central outlet coupling 23 in the pipe 24 leading to the pumps 16. The discharge in 25 this embodiment is at 25. The cone 26 is supported on feet 27 with its lower edge in a spaced relation to the bottom so that the material may flow to the central outlet. In this construction the distributing plates 28 30 form parts of the wheel, the outer ends of the plates being secured to a rim 29 carried by rollers 30, the inner ends of the plates being secured to a rotatable top section 31 of the cone. This rotating section 31 of the 35 cone is supported by the bearings 32 and the spindle 34. As the stock passes downwardly about the cone it strikes these plates 28 causing the rotation thereof, thus securing the rotary movement or agitation of the material in the tank. The embodiment shown 40 in Fig. II, however, has the advantage of being less complicated mechanically. By the aid of this apparatus I am enabled to disintegrate fibrous material, such as print 45 paper, to substantially its original pulp condition, that is, the fibres are not shortened or broken up as by grinding or coming in contact with a hard unyielding surface as the disintegration is effected by the pulling 50 or tearing action while the material is entirely suspended in the carrying liquid.

I have illustrated and described two embodiments of my invention which I believe will enable those skilled in the art to which 55 my invention relates to embody or adapt the same as conditions or uses may render desirable.

Having thus described my invention, what I claim as new and desire to secure 60 by Letters Patent, is:

1. In a stock treating machine, the combination of a cylindrical tank disposed vertically and having an inverted conical bottom, a cone disposed centrally within said tank, a plurality of transversely inclined 125 deflector plates disposed radially of said cone, a chamber having a central discharge opening above said cone, and a pump discharging into said chamber and having its intake connected to the bottom of said tank. 130

plates disposed radially at the upper end of said cone, a chamber having an inverted conical bottom with a central discharge opening, the top of the cone being close to and centrally of said discharge opening, 70 plates arranged on said nozzle chamber bottom to impart a rotary motion to the material discharged therethrough, and a pump discharging into said chamber and having its intake connected to the bottom of said 75 tank.

2. In a stock treating machine, the combination of a cylindrical tank disposed vertically and having an inverted conical bottom, a cone disposed centrally within said 80 tank, a plurality of transversely inclined deflector plates disposed radially at the upper end of said cone, a chamber having a central discharge opening above said cone, and a pump discharging into said chamber and 85 having its intake connected to the bottom of said tank.

3. In a stock treating machine, the combination of a cylindrical tank disposed vertically and having an inverted conical bottom, a cone disposed centrally within said tank, a chamber having an inverted conical bottom with a central discharge opening, the top of the cone being close to and centrally of said discharge opening, plates on said 90 nozzle chamber bottom to impart a rotary motion to the material discharged therethrough, and a pump discharging into said chamber and having its intake connected to the bottom of said tank. 95

4. In a stock treating machine, the combination of a cylindrical tank disposed vertically and having an inverted conical bottom, a cone disposed centrally within said tank, a chamber having a central discharge 100 opening, and a pump discharging into said chamber and having its intake connected to the bottom of said tank.

5. In a stock treating machine, the combination of a cylindrical tank disposed vertically, a cone disposed centrally within said tank, a plurality of transversely inclined deflector plates disposed radially of said cone, said plates having flanges on their rear edges and tapered transverse corrugations 110 extending partially across the same from their front edges, a chamber having a central discharge opening above said cone, and a pump discharging into said chamber and having its intake connected to the bottom 115 of said tank.

6. In a stock treating machine, the combination of a cylindrical tank disposed vertically, a cone disposed centrally within said tank, a plurality of transversely inclined 125 deflector plates disposed radially of said cone, a chamber having a central discharge opening above said cone, and a pump discharging into said chamber and having its intake connected to the bottom of said tank. 130

7. In a stock treating machine, the combination of a cylindrical tank disposed vertically, a cone disposed centrally within said tank, a chamber having a central discharge opening above said cone, and a pump discharging into said chamber and having its intake connected to the bottom of said tank. 5
8. In a stock treating machine, the combination of a cylindrical tank disposed vertically and having an inverted conical bottom terminating in an annular discharge trough, a central cone projecting upwardly from the inner edge of the discharge trough, a plurality of transversely inclined deflector plates disposed radially of said cone, a chamber above said cone having a central discharge opening, and a pump discharging into said chamber and having its intake connected to said discharge trough. 10
9. In a stock treating machine, the combination of a cylindrical tank disposed vertically and having an inverted conical bottom terminating in an annular discharge trough, a central cone projecting upwardly from the inner edge of the discharge trough, a chamber above said cone having a central discharge opening, and a pump discharging into said chamber and having its intake connected to said discharge trough. 15
10. In a stock treating machine, the combination of a cylindrical tank, a cone disposed centrally within said tank, a chamber having an opening centrally above said cone, means for imparting a rotary motion to the material delivered through said opening, means for imparting a rotary motion to the material about said cone, and a pump discharging into said chamber and having its intake connected to the bottom of said tank. 20
11. In a stock treating machine, the combination of a cylindrical tank, a cone disposed centrally within said tank, a chamber having an opening centrally above said cone, means for imparting a rotary motion to the material about said cone, and a pump discharging into said chamber and having its intake connected to the bottom of said tank. 25
12. In a stock treating machine, the combination of a cylindrical tank disposed vertically and having an inverted conical bottom terminating in an annular discharge trough, a central cone projecting upwardly from the inner edge of the discharge trough, a plurality of transversely inclined deflector plates disposed radially at the upper end of said cone, a nozzle chamber having a central discharge opening, the top of the cone being close to and centrally of said discharge opening, plates arranged on said nozzle chamber bottom to impart a rotary motion to the material discharged therethrough, nozzles discharging into said nozzle chamber so that the streams therefrom impinge within the nozzle chamber, and pumps having their intakes connected to 30
- 50
- 55
- 60
- 65
- said discharge trough and their discharges connected to said nozzles, all coacting for the purpose specified. 70
13. In a stock treating machine, the combination of a cylindrical tank disposed vertically and having an inverted conical bottom terminating in an annular discharge trough, a central cone projecting upwardly from the inner edge of the discharge trough, a nozzle chamber having a central discharge opening above said cone, nozzles discharging into said nozzle chamber so that the streams therefrom impinge within the nozzle chamber, and pumps having their intakes connected to said discharge trough and their discharges connected to said nozzles, all coacting for the purpose specified. 75
14. In a stock treating machine, the combination of a tank, a cone disposed centrally within said tank, a chamber having a discharge opening above said cone, means for imparting a rotary motion to the material about said cone, nozzles discharging into said chamber so that the streams therefrom impinge, and pumps having their intakes connected to the bottom of the tank and their discharges connected to said nozzles, all coacting for the purpose specified. 80
15. In a stock treating machine, the combination of a tank, a cone disposed centrally within said tank, a chamber having a discharge opening above said cone, nozzles discharging into said chamber so that the streams therefrom impinge, and pumps having their intakes connected to the bottom of the tank and their discharges connected to said nozzles, all coacting for the purpose specified. 85
16. In a stock treating machine, the combination of a stock tank, a chamber discharging into said tank, means for circulating the material within said tank, nozzles discharging into said chamber so that the streams therefrom impinge, the discharge of said chamber being in a plane below the nozzles and of such capacity that the streams are not subject to the pressure of a surrounding liquid, and pumps having their intakes connected to the bottom of the tank and their discharge connected to said nozzles. 90
17. The method of disintegrating paper consisting of discharging under pressure the paper to be disintegrated with a suspending or carrying liquid through nozzles disposed so that the material and liquid of one stream impinge with the material and liquid of another stream, the nozzles being spaced so that there is a substantial spreading of the streams at the point of their impingement. 110
18. The method of disintegrating paper consisting of discharging under pressure the paper to be disintegrated with a suspending or carrying liquid through nozzles disposed so that the material and liquid 120
- 125
- 130

of one stream impinges with the material and liquid of another stream and so that the streams from the nozzles are not confined by a surrounding liquid, the nozzles being spaced so that there is a substantial spreading of the stream at the point of impingement.

19. The method of disintegrating and deinking printed paper including the discharging under pressure of the paper to be disintegrated and deinked with a suspending or carrying deinking fluid through

nozzles disposed so that the material carried by one stream impinges with the material and liquid of another stream and so that the impinging streams are not surrounded by the liquid.

In witness whereof, I have hereunto set my hand and seal in the presence of two witnesses.

MILTON C. J. BILLINGHAM. [L. S.]
